UNITED STATES PATENT OFFICE.

GEORGE GORDON BROWN, OF LONDON, ENGLAND.

MEANS OF COMMUNICATION WITH THE BLIND.

1,178,991.

Specification of Letters Patent. Patented Apr. 11, 1916.

Application filed January 6, 1915. Serial No. 801.

To all whom it may concern:

Be it known that I, GEORGE GORDON BROWN, residing at 14 Beulah Hill, London, S. E., England, have invented certain new and useful Improvements in Means of Communication with the Blind; and I do hereby declare the following to be a full, clear, and exact description of the invention, such as will enable others skilled in the art to which it appertains to make and use the same.

This invention relates to a means for communicating with the blind and has for its object to provide a means for this purpose whereby reading or other matter may be communicated to the blind more cheaply than has heretofore been the case.

The present invention contemplates the employment of sheets or rolls of suitable flexible material which sheets or rolls are suitably perforated in a manner corresponding to the groups of points such as are at present used in Braille, New York point and other systems where groups of points are used to represent letters or words or 20 25 30 35 40 45 50 55 60 65 70 75 80 85 90 95 100 105 110 grams. The present invention provides a device whereby a perforated sheet of this nature can be traveled across the ends of a number of groups of pegs or pins which are pressed against the said sheet so that as each group of perforations is brought into position over the ends of the pegs included in one group, such pegs of that group as register with perforations in the sheet will project through the sheet for a limited distance where they can be felt by the reader's fingers. The pattern or arrangement of the groups of pegs and the perforations in the sheet will of course be in accordance with the pattern or arrangement employed in the particular system in use. The present invention will by way of example be described as applied to pegs arranged according to, and sheets perforated in accordance with the arrangement used in Braille where each group of pegs consists of six pegs arranged in two vertical columns of three each. The perforated sheet may be of any suitable width, for instance, it may be sufficiently wide so that it can accommodate a number of groups of perforations in its width with suitable spacing between.

The device which includes the groups of pegs also comprises means for accommodating a perforated roll or sheet and means for traveling the said sheet across the ends of the groups of pegs, and the arrangement

may be such that upon the key or device being operated the pegs are first depressed so as to free them from the perforations in the sheet. The sheet is then traveled across the ends of the pegs a distance sufficient to bring the next line of groups in alinement with the line of groups of pegs, the key being then released or returned to its original position causing the pegs to be free to move upwardly under the influence of certain springs so that these pegs which happen to register with perforations in the sheet will project therethrough.

The accompanying drawings illustrate by way of example one form of apparatus constructed in accordance with the present invention.

Figure 1 is a view in side elevation partly in section. Fig. 2 is a sectional view in end elevation.

In the construction shown in the drawings *a* is a roll of perforated material of any desired width. It will be understood that the roll *a* is perforated with lines or rows of groups of perforations which extend across the sheet, the said perforations being in accordance with the matter to be communicated. The roll *a* is mounted on a spool *b* which is mounted on an axle *b*¹. The sheet *a* after leaving the roll passes over a guide roller *c* mounted on an axle *c*¹ and thence across the ends of the pegs to a second guide roller *d* mounted on an axle *d*¹. After leaving the guide roller *d* the sheet *a* passes over a further guide roller *e* which is mounted on an axle *e*¹ and the sheet *a* passes from the roller *e* on to a second spool *f* mounted on a spindle *f*¹.

A suitable frame comprising uprights *g* and fixed connecting members *g*¹ *g*² is provided to accommodate the pegs *h*. Each peg *h* comprises a thin rod of metal or other suitable material adapted to slide up or down and supported in the cross members *g*¹ *g*² and also having a bearing in an additional member *j* which is mounted above the sheet *a* so that the said sheet is guided between the plate *j* and the plate *g*². Each peg *h* is provided with a fixed flange or collar *h*¹ and the lower parts of the pegs are encircled by springs *h*² which take a bearing at their lower ends against the member *g*¹ and at their upper ends against the flanges or collars *h*¹.

A movable cross member *k* is provided adapted to slide up and down on the up-

rights g below the collars or fixed flanges g^3 which serve to limit the upward movement of the cross member k . It will be seen that the springs h^2 acting against the collars h^1 on the pegs h will serve normally to keep the member k in its highest position abutting against the flanges or collars g^3 .

The member k can be moved downwardly when required by an eccentric l which is mounted on a spindle l^1 passing from side to side of the apparatus. The eccentric l is provided with an eccentric strap l^2 the ends of which are fastened to the member k . The eccentric strap l^2 may be guided in the member g^1 as shown in the drawing.

Means is provided for rotating the eccentric l when desired, the said means comprising a lever l^3 mounted on the spindle l^1 , the other end of the lever l^3 being connected to a link m . The upper end of the link m is connected to a pivoted lever n and n^1 and carrying a pawl o at its free end. The pawl o is connected to the lever n by a pivotal connection o^1 and a light spring o^2 is provided between the said pawl and the lever n so that the end of the said pawl is held in engagement with the teeth of a ratchet wheel e^2 mounted on the end of the spindle e^1 . Means is provided whereby the lever l^3 can be rocked when desired and also for simultaneously rocking the lever n and this means may comprise a vertical sliding rod p having a key or finger plate p^1 at its upper end. The spring p^2 is arranged to return the key p^1 to its highest position. The lower end of the rod p is connected to the junction of the link m and the lever n the arrangement being such that when the key p^1 is depressed the eccentric l is rocked pulling down the member k and thus freeing the pegs h from the sheet a . Simultaneously with the rocking of the lever l^3 the lever n is rocked on its pivot n^1 bringing the pawl o into engagement with the teeth of the ratchet wheel e^2 . This apparatus is so designed that the pawl o does not commence to rotate the ratchet e^2 until the pegs h have been freed from the sheet a .

The spool f on to which the sheet a is wound is rotated by a pulley or cord f^2 passing over pulleys f^3 e^3 .

The whole of this apparatus is contained within a suitable casing r having an opening r^1 in its top which opening is closed by the plate j which may be attached to the casing r . The top of the casing r consists of two hinged flaps r^2 r^2 which can be opened when desired for the insertion of fresh sheets and the removal of the sheets from the spools when desired.

From the foregoing description the use of the apparatus will be apparent, the sheet a being traveled from one spool to the other in the manner described and remaining stationary while the reader reads off each row

of groups of pegs as they project from the perforations provided.

What I claim and desire to secure by Letters Patent is:—

1. Means for communicating with the blind comprising a number of groups of resiliently mounted pegs, means for supporting a perforated sheet having rows of groups of perforations, means for bringing the rows of groups of perforations in the sheet successively into alinement with the row of groups of pegs whereby those pegs which register with perforations in the sheet may project therethrough. 75

2. Means for communicating with the blind comprising a number of groups of resiliently mounted pegs, means for supporting a perforated sheet having rows of groups of perforations, means for bringing the rows of groups of perforations in the sheet successively into alinement with the row of groups of pegs whereby those pegs which register with perforations in the sheet may project therethrough, and means for withdrawing said pegs from said perforations before the next row of groups of perforations in the sheet is brought into alinement with the row of pegs. 85

3. Means for communicating with the blind comprising a casing containing a number of groups of resiliently mounted pegs, a spool for supporting a perforated sheet, guide rollers and perforated guide plates whereby said sheet is guided across the ends of the row of groups of pegs, a winding 100 spool on to which the sheet is wound, a ratchet and pawl device for traveling said sheet intermittently so that the rows of groups of perforations are brought successively into alinement with the ends of the 105 pegs, and means for withdrawing the pegs from the perforations before the next row of groups of perforations in the sheet is brought into alinement with the row of pegs. 110

4. Means for communicating with the blind comprising a casing containing a frame in which is supported and guided a number of groups of resiliently mounted pegs, a member slideable on said frame and engaging abutments on said pegs, means for sliding said member on said frame whereby said pegs can be moved in an endwise direction when required, means in said casing for supporting a perforated sheet having 115 rows of groups of perforations, means for bringing the rows of groups of perforations in the sheet successively into alinement with the row of groups of pegs whereby those pegs which register with the perforations in 120 the sheet may project therethrough. 125

5. Means for communicating with the blind comprising a casing containing a frame in which is supported and guided a number of groups of resiliently mounted 130

5 pegs, a member slideable on said frame and engaging abutments on said pegs, an eccentric for sliding said member on said frame whereby said pegs can be moved in an end-
wise direction when required, a spool for supporting a perforated sheet, guide rollers and perforated guide plates whereby said sheet is guided across the ends of the row of groups of pegs, a winding spool on to which
10 the sheet is wound, a ratchet and pawl device for traveling said sheet intermittently so that the rows of groups of perforations are brought successively into alinement with

the ends of the pegs, and means for operating said eccentric and said ratchet and pawl mechanism simultaneously so that the ends of the pegs are withdrawn from the perforations before the next row of groups of perforations in the sheet is brought into alinement with the row of pegs.

15 In testimony whereof I affix my signature, in presence of two witnesses.

GEORGE GORDON BROWN.
